UNITED STATES PATENT OFFICE

151,219

DESIGN FOR A TURBINE JET AIRCRAFT ENGINE

Milton U. Clauser, Los Angeles, and Arlton N. Hatch, Santa Monica, Calif., assignors to Douglas Aircraft Company, Inc., Santa Monica, Calif.

Application July 2, 1946, Serial No. 131,280

Term of patent 7 years

(Cl. D71—1)

To all whom it may concern:

Be it known that we, Milton U. Clauser and Arlton N. Hatch, citizens of the United States and residents, respectively, of Los Angeles, in the county of Los Angeles and State of California, and Santa Monica, in the county of Los Angeles and State of California, have invented a new, original, and ornamental Design for a Turbine Jet Aircraft Engine, of which the following is a specification, reference being had to the accompanying drawings, forming a part thereof.

Figure 1 is a perspective view of a turbine jet aircraft engine showing our new design with the propellers thereof shown in phantom lines;

Figure 2 is a top plan view of the subject turbine jet aircraft engine with the propellers shown in phantom lines;

Figure 3 is a front elevational view thereof with the propellers shown in phantom lines;

Figure 4 is a bottom plan view thereof with the propellers shown in phantom lines; and

Figure 5 is a rear elevational view thereof with the propellers shown in phantom lines.

The phantom line showing of the propellers in the several figures of the drawing is for illustrative purposes only.

We claim:

The ornamental design for a turbine jet aircraft engine, substantially as shown and described.

MILTON U. CLAUSER.
ARLTON N. HATCH.
